UNITED STATES PATENT OFFICE.

CHARLES WURTEMBERG, OF UNION CITY, CONNECTICUT.

BREAD SLICER.

Application filed January 26, 1928. Serial No. 249,740.

The invention relates to improvements in slicing devices and the present disclosure is devoted to one designed primarily for slicing bread, the principal object being to provide 5 novel means whereby a slicing knife is held in a truly horizontal position and is guided vertically to produce accurate cuts in an easy manner.

Another object is to provide a slicer of 10 new and improved form, embodying a base to which knife-guiding means is pivoted for downward folding against said base when not in use, unique provision being made whereby said guiding means is held in 15 upright position for use, whenever desired.

With the foregoing in view, the invention resides in the novel subject matter hereinafter described and claimed, description being accomplished by reference to the accompanying 20 drawing.

Fig. 1 is an end elevation of a slicer constructed in accordance with my invention, the knife being in raised position.

Fig. 2 is a view similar to Fig. 1, on a reduced scale showing the knife lowered.

Fig. 3 is a top plan view.

Fig. 4 is a side elevation with the knife in section.

Fig. 5 is a fragmentary perspective view. 30 The drawing above briefly described illustrates the preferred form of construction, and while this construction will be herein specifically explained, it is to be understood that within the scope of the invention as 35 claimed, variations may be made.

5 denotes a rectangular base provided along one longitudinal edge with an up-standing guide wall 6 against which to rest a loaf of bread to be sliced. At one end, 40 the base 5 is formed with a horizontal kerf 7 which opens laterally through one of its edges. Contacting with this edge of the base is a horizontal metal strip 8 which is pivoted to said edge on a suitable transverse pivot 9, the free end of the strip 8 being formed with a keeper or notch 10 which alines with the kerf 7, when the strip 8 is horizontal as in Fig. 4. A latch 11 is pivoted 45 at 12 in the kerf 7 and when swung into the keeper or notch 10, holds the strip 8 in horizontal position.

Pivoted at 13 to the edge of the base 5 opposite the strip 8, is a similar strip 14, the pivots 9-13 being alined. The legs of an 55 arched, knife-guiding frame 15, are secured by rivets or the like 16 to the strips 8-14

and when the latch 11 is in operative position, said frame is held upright. Release of the latch however, permits the strips 8-14 to swing, and the frame 15 may then swing 60 downwardly against the base 5, producing a very compact structure when its use is not necessary.

Frame 15 is preferably formed of two arched metal bars spaced apart to provide 65 a guiding slot 16 for a knife 17, and unique provision, now to be described, is provided to insure that the knife shall remain in a truly horizontal position, but may readily move upwardly and downwardly.

Two lugs 18-19 are suitably secured to and rise from the upper corner portions of the frame 15, these lugs being instrumental in connecting two, inclined, crossed levers 20-21 with said frame. The ends of these 75 levers are denoted at 20^a-20^b and 21^a-21^b, and as the ends 20^a and 21^a are the lowermost throughout probably the greater part of a slicing operation, they will be herein-after referred to as the lower ends of the 80 levers, permitting a clearer description than would otherwise be possible. The lower end 20^a of lever 20 is pivoted at 22 to the lug 19, while the lower end 21^a of lever 21 is pivoted at 23 to a short link 24, the lower end of 85 the latter being pivoted at 25 to the lug 18. The two levers 20-21 are pivoted to each other at 26, lever 20 being provided with a laterally offset portion 27 through which this pivot passes. The numerous pivots 90 22-23-25-26 are all parallel and hence the levers 20-21 may swing upwardly and downwardly but this swinging is necessarily uniform, due to the arrangement of parts shown and described.

95 Relatively long links 28-29 are pivotally hung from the upper ends 20^b-21^b of the levers 20-21 respectively, the pivots 30 which connect said links and levers being parallel with the pivots above described. 100 The lower ends of the links 28-29 are pivoted by removable pins or the like 31, to the end portions of the knife 17. Thus, the knife may be readily reciprocated by hand and as it moves downwardly during the cutting operation, it is maintained in parallel 105 relation with the base 5. By the time it has completed a cut, the lateral portion 27 of lever 20, strikes the crown portion 32 of the frame 15 and limits the descent of said 110 knife, preventing it from cutting the base.

It will be seen from the foregoing that

a slicer of very novel and advantageous construction has been provided for successfully slicing bread or in fact any object which may readily be sliced, and the thickness of the slices may be controlled by an appropriate adjustable gauge 33.

Attention is again invited to the fact that while the preferred form of construction has been illustrated and specifically described, variations may be made within the scope of the invention as claimed.

I claim:—

- 15 1. A slicer comprising a support, link-supporting means mounted thereon and embodying front and rear link pivots and means for insuring uniform vertical movement of said pivots, front and rear links hung from said pivots, and a knife pivoted to the lower ends of said links, said link-supporting means permitting vertical movement of said links and knife independently of swinging of said links, said links permitting continual reciprocation of the knife while making a cut.
- 20 2. A slicer comprising a support, a pair of crossed oppositely inclined levers pivoted together, means fulcruming the lower end of one of said levers to said support, means connecting the lower end of the other lever

to the support and permitting movement of this lever end toward and from said lower end of said one lever, links pivotally hung from the upper ends of said levers, and a knife pivoted to the lower ends of said links.

3. A slicer comprising a support, a pair of crossed oppositely inclined levers pivoted together, means fulcruming the lower end of one of said levers to said support, a link pivoted to the lower end of the other lever and to said support, relatively long links pivotally hung from the upper ends of said levers, and a knife pivoted to the lower ends of said long links.

4. A slicer comprising a base, an arched knife-guiding frame rising from said base, a pair of crossed oppositely inclined levers pivoted together and disposed at the crown portion of said frame, means fulcruming the lower end of one of said levers to said frame, a link pivoted to the lower end of the other lever and to said frame, relatively long links pivotally hung from the upper ends of said levers, and a knife pivoted to the lower ends of said long links and slidably engaged with said frame.

In testimony whereof I have hereunto affixed my signature.

CHARLES WURTENBERG.
